REST FOR A SMOKING PIPE

Nicholas P. Angelakos, Brooklyn, N.Y., assignor to Lancaster Colony Corporation, a corporation of Delaware

Filed Aug. 8, 1969, Ser. No. 18,590

Term of patent 14 years

Int. Cl. D27—02

U.S. Cl. D85—8

FIG. 1

FIG. 6

FIG. 2

FIG. 5

FIG. 3

FIG.9

FIG.10

FIG.8

FIG.11

FIG. 1 is a perspective view of a rest for a smoking pipe showing my new design;

FIG. 2 is a top view;
 FIG. 3 is a side view;
 FIG. 4 is a front view;
 FIG. 5 is a rear view;
 FIG. 6 is a bottom view;

FIG. 7 is a bottom view of another embodiment of a rest for a smoking pipe showing my new design;

FIG. 8 is a top view;
 FIG. 9 is a rear view;
 FIG. 10 is a front view; and
 FIG. 11 is a side view.

I claim:

The ornamental design for a rest for a smoking pipe, substantially as shown and described.
